UNITED STATES PATENT OFFICE

WILLIAM E. FOWLER, SR., OF CHICAGO, ILLINOIS, ASSIGNOR TO THE FOWLER CAR COMPANY, OF CHICAGO, ILLINOIS, A CORPORATION OF ILLINOIS.

STEEL-SHEATHED BOX-CAR.

1,225,948.

Specification of Letters Patent.

Patented May 15, 1917.

Original application filed May 28, 1914, Serial No. 841,465. Divided and this application filed February 17, 1915. Serial No. 8,756.

To all whom it may concern:

Be it known that I, WILLIAM E. FOWLER, Sr., a citizen of the United States, and resident of Chicago, in the county of Cook and

5 State of Illinois, have invented certain new and useful Improvements in Steel-Sheathed Box-Cars, of which the following is a specification.

My invention relates to railway cars and 10 has particular reference to a novel steel-sheathed box car, such as shown in my Patent No. 1,151,351 of August 24, 1915, of which this is a division.

An object in the present construction is 15 to provide a car of steel exterior, and, if desired, with a wooden interior, for the purpose of insulation which shall be so constructed as shall obviate the necessity for framing, the load being carried by the walls 20 themselves.

A further object is to provide means in connection with such a car whereby a wooden sheathing may be readily applied if desired, the interior surface including side and 25 end walls, floor and roof, being adaptable to the application or omission of the wooden sheathing element.

For many uses a car composed of a single steel sheathing would be satisfactory but 30 such cars are not available for general service unless provision is made for the attachment to the interior of bracing for securing certain types of lading. Such bracing cannot be readily secured without the 35 provision of wooden posts to which the bracing would be nailed.

Preferably the wooden posts are secured in the channels formed at the juncture of the side plates by means of bolts or rivets 40 which extend in a line parallel with the plane of the plates. Thus the tendency of the channels to open up under strain is overcome. The sides should not be relied upon to carry the load without this provision inasmuch as the strength of the plates against 45 elongation would only be the elastic limit of the metal forming the channel.

In the present construction an object is to 50 so join the abutting edges of the plates that economy in the use of material is effected; furthermore to provide means for joining the edges, such as by the use of rivets, such means being independent of the means used

for fastening the wooden posts in place. The invention would be more readily understood by reference to the accompanying drawings, wherein:

Figure 1 is a side elevation of a portion of a railway car constructed in accordance with my invention,

Fig. 2 is a fragmentary longitudinal section of the same, and

Fig. 3 is an enlarged view of a portion of the construction shown in Fig. 2.

Referring more particularly to the drawings, it will be seen that the car ends and sides may consist in plates 10 having, if desired, a channel 11 formed intermediate the edges of the plates, this channel serving to strengthen and give rigidity to the sides. 65 The side edges of each of the plates are bent into an angle, as shown at 12, the marginal edges of adjacent plates being overlapped and riveted, as shown at 13.

The upper and lower edges of the plates 75 10 are flanged, as at 14, the flanges of adjacent plates being overlapped and riveted. At the ends I prefer to bend the plate 15, composing the end wall in such manner as to provide for the accommodation of a substantial post 16, the end and side sheets being overlapped, however, in the same manner as just described. It will be seen that in the side and end walls the flanging of the adjacent sheets forms a channel and in this 80 channel I locate a post 17, one edge of which projects beyond the inside plane of the sheets. To this post may be secured boards 18 by the use of nails or other suitable means. This leaves the space 19 between 85 the wooden and metallic members which serves as an effective insulation. Likewise I mount a post 20 in the channel formed by the strengthening rib 11. In order to strengthen the structure and at the same 90 time removably secure the posts 17 and 20 in place, I provide bolts 21 which pass through the metallic and wooden members in the plane of the car side. The object sought in thus locating such bolts is to prevent 95 the spreading of the channels under certain strains, the side walls thereby acting as girders which serve to carry the load. Of course, these channels might be bridged by other means than the bolts 21 and at the same 100 time maintain the posts in position and it

is to be understood that any equivalent means for preventing the spreading of the channels is contemplated by me.

I claim:

5 1. In a railway car, the combination of a side wall composed of a plurality of sheets or plates, the marginal edges of which are bent into L-shape, the terminal flanges of adjacent L-shaped portions being overlapped and riveted, the channel-shaped space formed by such construction being open to the inside of the car and being adapted to receive a wooden post.

15 2. In a railway car, the combination of a sheathing composed of metallic sheets, two of the marginal edges of each of which sheets are bent and overlapped to form channels, said channels extending outside of the plane of the sheets, means for securing together

the overlapped portions of the sheets, and means extending parallel to the plane of the side of the car for bridging said channels and preventing their spreading under strain, substantially as described.

3. A car end constructed of a plurality of 25 alined metal plates having their meeting edges constructed in Z-shape, the lateral ribs whereof extend outwardly beyond the plane of the plates and the vertical flanges whereof overlap and are connected together in channel-beam formation.

Signed at Chicago, Illinois, this 13th day of February, 1915.

WILLIAM E. FOWLER, Sr.
